CONTAINER

Arthur W. Van Dyke, Elizabeth, N. J., assignor to The Diamond Match Company, New York, N. Y., a corporation of Delaware

Application February 12, 1954, Serial No. 409,865

3 Claims. (Cl. 229—31)

The present invention relates to a container for packaging and displaying food products or the like. More particularly, the present invention relates to a container that is folded from a blank form or molded from a pulp material, the container including supporting means which provide for the stacking of the container with other containers and which furthermore protect an article disposed in the container.

The container embodied in the present invention is directed toward the open type container and is distinguished from the cellular container, which is defined as that type which is formed with a plurality of cells, the cells being adapted to receive eggs or other frangible objects therein.

Prior to the instant invention, the open type containers known heretofore, which have been utilized for the purpose of packaging and displaying of food products or the like, were formed with a cover member if it were desirable to stack the containers one upon the other. Stacking the containers is oftentimes necessary since the article disposed therein must be protected from crushing. However, by utilizing a separate cover member with the container, additional folding was necessary when the carton was originally formed or, if the carton were formed of a molded pulp material, a separate cover section had to be molded with the container. This additional cover section necessarily increased the cost of the complete container. Moreover, if the container were molded, the additional cover section created a shipping and storing problem since the containers could not be nested within one another.

It is therefore an object of the present invention to provide an open type container that is formed with corner supporting members which provide for the stacking of the container with similarly formed containers, thereby eliminating the need of a cover member.

It is still another object of the present invention to provide a container that is formed from a blank and folded so as to form corner supporting members, the corner supporting members providing for the stacking of the container.

Still another object of the present invention is to provide a container that is formed on a single mold and stripped therefrom, the walls of the container being molded in generally divergent relation, thereby providing for the nesting of the container with similarly formed containers for shipping or storing.

Still another object of the present invention is to provide a container that is formed with a plurality of corner posts, the corner posts forming supporting means for supporting similarly formed containers thereon.

Still another object of the present invention is to provide a container that is provided with a plurality of corner posts, each of the corner posts being formed with a top panel, the top panels forming supports for receiving other similarly formed containers thereon.

Other objects and the nature and advantages of the

2

instant invention will be apparent from the following description taken in conjunction with the accompanying drawings, wherein:

Fig. 1 is a plan view of the blank from which the container embodied in the present invention is formed;

Fig. 2 is a plan view of the container embodied in the present invention in the folded position and as it is used for the display of articles disposed therein;

Fig. 3 is an end elevational view of the container illustrated in Fig. 3;

Fig. 4 is a section taken on the line 4—4 of Fig. 3;

Fig. 5 is a perspective view of the corner posts of the container embodied in the present invention;

Fig. 6 is a bottom plan view of a portion of the container embodied herein, illustrating the molded position of a corner post when the container is stripped from a single mold;

Fig. 7 is an elevational view of the portion of the container illustrated in Fig. 6; and

Fig. 8 is a section taken on the line 8—8 of Fig. 6.

In one form of the present invention, the container is adapted to be formed from a cardboard or paper blank and folded from the blank form to the box formation along scored fold lines. For the purpose of describing the present invention, the completely folded position of the container or box is defined as the "display position" since this is the position in which the container receives articles for display or packaging. The container shown and described herein may also be molded from a pulp material and as molded is defined as being formed in a "nesting position." In the molded or nesting position, the walls of the container are formed in divergent relation to one another and thereby provide for nesting of the container with other containers for the purpose of shipping or storing, the container walls being subsequently moved to a display position, as will be more fully described hereinafter.

Referring now to Fig. 1, the container in blank form is illustrated and this form of the invention will now be described. The container blank is generally indicated at 10 and as illustrated is adapted to be folded into the box formation shown in Figs. 2—5. The blank 10 comprises a bottom wall 12 which has side walls 16 joined thereto along the fold lines 14. The bottom wall 12 has holes

13 formed therein which are provided for decreasing the weight of the container. It is also understood that the holes 13 may be provided for ventilating purposes and/or for viewing the article in the container from the bottom. The side walls 16 are formed with portions cut out therefrom, the cut-out portions being defined between the points 18, and thereby enabling the food article when disposed in the folded container to be more easily viewed. Joined to each of the side walls 16 and forming the corners of the container are corner posts which are generally indicated at 20. Each of the corner posts 20, which form supporting means for supporting other similarly formed containers or other objects thereon for protecting objects disposed in the container, comprises side panels 22 which are joined to the side walls 16 along fold lines 24. The side panels 22 in the blank form are continuations of the side walls 16 and are defined by the fold lines 24 and the fold lines 26, thereby forming right triangles. Interposed between the side panels 22 is a supporting panel 28 which is joined to the side panels 22 along the fold lines 26 and is formed as an isosceles triangle, the two equal legs of the isosceles triangle being defined by the fold lines 26. The side panels 22 and supporting panel 28, all of which have a triangular configuration, have one common apex

30 which is located at the point 30, the point 30 defining the intersection of the fold lines 24 with the fold lines 26. Joined to the supporting panel 28 along a fold line 31

is a top panel 32 which forms the upper surface of the supporting post when the blank is folded into the display position. Extensions 34 are joined to the top panel 32 along fold lines 36 and have locking flaps 38 formed thereon, the locking flaps 38 being adapted to be received by slits 40 formed in the side walls 16 and thereby providing means for locking the corner posts 20 into secure engagement with the side walls 16 when the container is folded into the display position.

When the blank 10 of the container embodied herein is folded from the blank form shown in Fig. 1 into the display position illustrated in Figs. 2, 3 and 4, the side walls 16 are folded along the fold lines 14 until they are perpendicular to the bottom wall 12. In moving the side walls 16 to this position, the side panels 22 of the corner posts 20 are folded along the fold lines 24 until they are in face-to-face relation with the inner surface of the side walls 16. The fold lines 24 are then located adjacent to each other and define inner corners of the container. With the side panels 22 in face-to-face relation with the inner surface of the side walls 16, the supporting panel 28 extends upwardly from the point 30 and in divergent relation with respect to the bottom wall 12, the upper edge of the supporting panel 28 defined by the fold line 31 overhanging the point 30, as shown in Fig. 4. In this position, the extreme end points of the fold line 31, which are defined by the intersection of fold lines 26 with fold line 31, coincide with the points 18 formed from the cut-out portions of the side walls 16, as shown in Figs. 2-5. The top panel 32 is next folded along the fold line 31 and is positioned in parallel relation with respect to the bottom wall 12, but is located in divergent relation with respect to the supporting panel 28, as illustrated particularly in Fig. 4. In the folded or display position, the side panels 22, supporting panels 28 and top panels 32 define inverted pyramids, an apex of each pyramid being located at each of the points 30. Since the supporting panels 28 are formed as isosceles triangles, and the side panels are formed as right triangles, the sides of the inverted pyramid are not equal. However, this construction enables the inverted pyramids to formfit the corners defined by the side walls 16, the side panels 22 lying along the inner surface of the side walls and the supporting panels 28 extending between the side walls and being inclined so that the upper edges thereof overhang the apices or points 30. In order to complete the folding of the corner posts, the extensions 34 are folded along the fold lines 36 into face-to-face relation with the outer surfaces of the side walls 16, inner edges 42 of the extensions 34 meeting and overlying the inner corners defined by the fold lines 24 and thereby forming the outer corners of the folded container. The locking flaps 38 are then inserted into the slits 40 to lock the corner posts to the side walls 16. If it is required, the extensions 36 may be securely fastened together at the inner edges 42 by applying a suitable paper adhesive around the aforesaid edges 42.

When the container has been folded into the display position from the blank illustrated in Fig. 1, the top panels 32 of the corner posts 20 define supporting surfaces for receiving thereon other objects or loads or similarly formed containers. This provides for stacking of the containers, thereby conserving valuable storage space and furthermore providing for the protection of an article that may be positioned within the interior of the container. The supporting panels 28 which are joined to the top panels 32 and are divergent thereto are adapted to transfer any load carried by the top panels 32 to the lowermost corners of the container. By transferring the load on the top panels 32 to the lowermost corners of the container, large loads may be carried by the container and many containers may be loaded and stacked one upon the other without fear of crushing the article positioned in each container. The container may be easily formed in the blank form and by scoring the blank to form the fold lines indicated, the

blank may be simply and quickly folded into the display position.

Referring now to Figs. 6-8, the container described herein is illustrated as it is formed when molded from a pulp material. The container when molded is adapted to be stripped from a single mold and in the molded form defines an open or nesting position. By forming the container in the nesting position, the container may be nested with other similarly formed containers and thereby a large number of containers may be shipped or stored in a relatively small area. As shown in Figs. 6-8, the side walls of the container and the corner post panels, when molded in the nesting position, are formed divergent to the container bottom wall 12. By molding the container walls and corner post panels in the nesting position, the stripping operation for removing the container from the mold is greatly facilitated since the container side walls and corner post panels are located in divergent relation with respect to the bottom wall 12. The container as molded includes the identical elements as described hereinabove in connection with the blank 10. Therefore, when the container is moved from the molded or nesting position to the display position, the movement of the side walls 16 and corner post panels 22, 28, 32 and 34 along their respective fold lines is accomplished in the same manner as set forth hereinabove. The molded container does differ from the container blank 10 in that the extensions 34, as molded, are joined along the edges 42. Thus, when the molded corner posts 20 are moved into the locked position with the side walls 16, the extensions 34 are already joined, thereby obviating the use of an adhesive paper or the like, which had been described above as being desirable for securing the extensions of the blank.

By referring particularly to Fig. 6, it is at once apparent that the corner posts 20, as molded, may be simply and quickly folded to the display position since the corner post panels 22, 28, 32 and 34 are located in divergent position to one another, thereby defining the fold lines therebetween. After the side walls 16 have been folded so that they are perpendicular to the bottom wall 12, the side panels 22 are folded into face-to-face relation along the inner surface of the side walls 16. This automatically positions the supporting panel 28 between the side walls 16 to form the inverted pyramid. The corner post is completed by folding the top panel 32 over the inverted pyramid, folding down the extensions 34 into face-to-face relation with the outer surface of the side walls 16, and inserting the locking flaps 38 into the slits 40.

It is apparent that since the container illustrated in Figs. 6-8 is formed from a molded pulp material, it has a more rigid and stable construction than the container folded from the cardboard blank 10. However, both embodiments incorporate the new type corner post, which, whether formed by folding from a blank or from a molded pulp material, is an extremely strong construction and is capable of withstanding heavy loads placed thereon.

The present invention provides a container that is not only economically desirable to manufacture but also enables the user to conserve valuable storage or shipping space whether the container is utilized in blank form or molded form. The container in the molded form may be nested for shipment or storage with as many containers as practically possible and then simply and quickly moved to the display position to receive an article for display therein. The container, in addition to protecting the article disposed therein, provides an open container for fully viewing the article. If desirable, a convenient overwrap may be wrapped around the top of the article and secured to the underside of the container by some convenient means.

It will be obvious to those skilled in the art that various changes may be made without departing from the spirit

of the invention and therefore the invention is not limited to what is shown in the drawings and described in the specification but only as indicated in the appended claims.

What is claimed is:

1. In a container, a bottom wall, side walls joined to said bottom wall and having slits formed therein adjacent the ends thereof, corner posts interconnecting said side walls and forming the corners of said container, each of said corner posts including triangular side panels, said side panels being located in face-to-face relation with the inner surfaces of said side walls, a supporting panel having a triangular configuration and cooperating with said triangular side panels to define an inverted pyramid, the apex of said pyramid coinciding with the intersection of the bottom edges of side walls, and a top panel joined to each supporting panel and forming the top of the inverted pyramid, each of said top panels being formed in a right angle triangle, the hypotenuse of which is joined to said triangular supporting panel, extensions joined to the other sides of each of said top panels and having locking flaps formed thereon, said locking flaps being received by said slits in said side walls to lock said corner posts in position, said extensions being located in face-to-face relation with the outer surfaces of said side walls.

2. In a molded pulp container, a bottom wall, side walls hingedly joined to said bottom wall and located in non-planar relation thereto, corner posts joined to said side walls, each of said corner posts including a supporting panel, side panels hingedly joined to the sides of said supporting panel and an end of said side walls in non-planar relation thereto, a top panel hingedly joined to a third side of said supporting panel in non-planar

relation thereto, and extensions hingedly joined to said top panel in non-planar relation thereto, each of said extensions including means for engaging the side wall adjacent thereto for locking said corner posts to said side walls, said non-planar walls and panels being hingedly moved from the molded position to a position of use, whereby said side walls are perpendicular to said bottom wall, said corner post side panels are located in face-to-face relation with the inner surface of said side walls, said corner post top panels are parallel to said bottom wall and divergent to said supporting wall and said extensions are located in face-to-face relation with the outer surface of said side walls.

3. In a molded pulp container as set forth in claim 2, said side walls having slits formed therein, and said engaging means being defined by locking flaps, said slits receiving said locking flaps therein for locking said corner posts to said side walls.
